(57) **CLAIM**

The ornamental design for a dynamic entry tool, as shown and described.

DESCRIPTION

FIG. 1 is a front view of the present invention dynamic entry tool;

FIG. 2 is a rear view of the present invention dynamic entry tool shown in FIG. 1 above;

FIG. 3 is a right side view of the present invention dynamic entry tool shown in FIG. 1 above;

FIG. 4 is a left side view of the present invention dynamic entry tool shown in FIG. 1 above;

FIG. 5 is a top view of the present invention dynamic entry tool shown in FIG. 1 above; and,

FIG. 6 is a bottom view of the present invention dynamic entry tool shown in FIG. 1 above.

1 Claim, 6 Drawing Sheets
